(57) **CLAIM**

The ornamental design for a vaporizer battery pod as shown and described.

DESCRIPTION

FIG. 1 is a front perspective view of a vaporizer battery pod showing my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a front perspective view of the vaporizer battery pod with a cap;

FIG. 10 is a rear perspective view of the vaporizer battery pod with the cap; and,

FIG. 11 is a bottom perspective view of the vaporizer battery pod with the cap.

The broken line portions of the vaporizer battery pod in FIGS. 1–11 represent unclaimed portions of the article and form no part thereof. The broken lines of the cap in FIGS. 9–11 illustrate unclaimed environment and form no part of the claimed design.

1 Claim, 10 Drawing Sheets
